(57) CLAIM

The ornamental design for a “seed tube guard”, as shown and described.

DESCRIPTION

FIG. 1 is a left side elevational view of the upper left side of the “seed tube guard”;

FIG. 2 is a rear elevational view;

FIG. 3 is a front elevational view;

FIG. 4 is a sectional view taken along Line 4—4 of FIG. 2;

FIG. 5 is a top view;

FIG. 6 is a bottom view; and,

FIG. 7 is an enlarged perspective view from the upper left side.

The right side is a mirror image of the left side and the opposite end view is likewise a mirror image of FIG. 3.
